CONTACT PLUG

Arthur Brownstein, Bridgeport, Conn., assignor
to Electrix Corporation, Pawtucket, R. I., a corporation of Rhode Island

Application March 5, 1937, Serial No. 129,235

3 Claims. (Cl. 173—361)

This invention relates to a new and useful contact plug and more particularly to a resilient contact plug. A contact plug so-called generally refers to the bladed fixture at the end of a wire conductor which makes the necessary electrical contact when pushed into the complementary recesses in an electrical outlet or other suitable socket, all as hereinbelow described.

Resilient contact plugs or rubber contact plugs

- 10 as they are commonly called because rubber is the insulating material usually used in their manufacture, are favorably received in the electrical trade. Unlike molded resins, hard rubber or similar contact plugs they are not subject to easy fracture and inasmuch as they are pliable the contact or connector blades can adjust themselves to small variations in the gauge or distance between socket recesses. Further, connector blades are more easily and quickly assembled in
- 15 resilient plugs, generally a simple punch operation will suffice and then, too, there is no need of rivets, screws or other holding devices. With the harder contact plugs, blades frequently work loose, impair the electrical efficiency of the plug
- 20 and prove a nuisance in general; with resilient contact plugs, the connector blades, on the other hand, are more cheaply, easily and lastingly retained. Another desirable point is that the electrical joints between the blades and wire conductors ends in a resilient plug are more adequately guarded from strain and insulated in and by the plug itself. Yet, resilient contact plugs can be molded with ease and at low cost.

Prior to this invention and at present, resilient contact plugs have been and are made and sold in which the connector blades are retained by distortion of the rubber. There are certain drawbacks in this type of resilient plug. In the first place, the connector blades are not too securely held because the very portion of each blade relied upon to produce the desired distortion for purposes of holding the blade in place in the plug at the same time prevents maximum surface contact between the surface of the blade and the adjacent surfaces of the plug. To remedy the wobble induced thereby, recourse frequently is had to a wedging piece to be tightly fitted into the plug between the blades. This wedging piece has a steadyng effect on the blades relative to the plug and resists their being pulled out with undue ease. A second type of resilient plug has the blades and wire conductor on the underside of a substantial rubber block over which fits a rubber cap threaded on the wire conductor

the block through which the blades protrude. This two piece plug is liable to having its parts separate, is very expensive and lacks the more secure holding of the blades which is an object of this invention.

It is the object of this invention to produce a resilient contact plug in which the connector blades are held in a positive manner against movement in either direction along their longitudinal axes. It is also an object of this invention to produce a contact plug of this type having but one part i. e., a one-piece plug.

It is also an object of my invention to produce a resilient contact plug in which there is maximum surface contact between the connector blades and the plug body and at the same time the blades are prevented by positive means from being pulled out of or pushed down into the body of the plug.

It is also a primary object of this invention to achieve a new and important method of assembling connector blades and resilient contact plug bodies. A further object is a resilient contact plug in which the connector blades and wire conductor ends are assembled from the small end of the plug.

A further object is the production of a resilient contact plug in which there are positive restraining means for the conductor blades and yet which is successfully moldable. Particularly is this an object in connection with the "one-piece" contact plug which is an object of this invention.

In a preferred embodiment of this invention there is a one-piece molded body of such a construction that in the assembly thereof the blades and conductor wires therefor are inserted through the small end of the contact plug into proper slots therefor provided until the blades reach and are held by positive means in their permanent position. The body of this plug is molded so that while the mold dies are being withdrawn there is no undue tearing or straining of any part of the body of the plug. This preferred form of contact plug has two blade slots of rectangular cross-section which extend into the interior of the plug and there join to form a common channel opening out at the small end thereof. This channel forks at the point where it divides and its parts join the lower ends of the respective blade slots. Blade slots are commonly made of slightly smaller dimension than the blade in cross-section so as frictionally to grip and hold the blade when it is assembled in place.

Near the lower end of each blade slot are to be found small integral blocks of equal size on opposite sides of the slot. These blocks thus constrict the passage through the slot except for a relatively smaller passage therebetween. Placed in this fashion the blocks are adapted to engage in complementary recesses in the blades when they are assembled therewith. Thus the blades are held against sidewise movement by the sides of the slots and against endwise movement in either direction by the blocks and blade recesses.

Each blade is a relatively flat, rectangular, metallic conductor adapted to extend beyond the usual flat face of the large end of the contact plug so that when inserted into the electrically live socket it performs the electrical conduction connector service that is required. Such a blade to be used with the contact plug of this invention should preferably be recessed to engage with the blocks previously described and the ends thereof may be beveled or curved so that when the blades and plug body are assembled together the passage of each blade through the constricted portion between the blocks is effected easily because the blocks separate sufficiently when pushed back because of the resilient material in the plug. When the blocks are opposite to the blade recesses they snap into positive engagement fixing the blade in place and effecting one of the objects of this invention.

In assembling the preferred embodiment of the contact plug of this invention, it must be done, of course, as will appear in more detail below, through the small end thereof. At the point where the channel therein forks, the dividing wall serves as a guide for the blades being pressed towards their respective slots.

Although the preferred embodiment just described has certain physical characteristics, it is entirely possible at the same time to stay within the spirit of this invention and yet depart from the precise form thereof by the exercise of mechanical skill. For example, the blocks located in the blade slots may be one in number or more, may be set opposite to one another or may be staggered along the length of the slot. Likewise for example, each blade slot may be extended further into the contact plug and the blocks located at any point along its length. Further, the guide wall of the channel at the lower end of the blade slots might be completely removed or on the other hand it might be increased in size even to the point where there will be two separated combination blade slots and channels extending through the plug from one end to the other.

Another change that can be made is to remove excess material from the plug parallel to the plane of the two blades and thus produce a flatter plug. There is even a possibility that the blades can carry the blocks and the slots have the recesses. In such a case, a special mold die would have to be made.

Other objects, advantages and features of this invention will appear from the drawing and the following description.

In the drawing:

Fig. 1 is a perspective view of a contact plug embodying this invention in full assembled relation with the wire conductors therefor;

Fig. 2 is a top view of the contact plug of Figure 1;

Fig. 3 is a cross-sectional view taken on line 75 3-3 of Figure 2;

Fig. 4 is a cross-sectional view taken on line 4-4 of Fig. 3;

Fig. 5 is a cross-sectional view through the center of the body of the contact plug shown in Figure 1;

Fig. 5-A is the three-part mold including plungers for the plug body;

Fig. 6 is a perspective view of the body of a contact plug which is a preferred embodiment of this invention;

Fig. 7 is a cross-sectional view through the center of the body of the contact plug shown in Figure 6;

Fig. 8 is a view in perspective elevation of connector blades ready for insertion into the body 15 of the contact plug of this invention; and

Fig. 9 is a cross-sectional view in elevation of the contact plug assembly.

Referring to the drawing, 10 is the body of the form of a resilient contact plug covered by 20 this invention shown in Figures 1 through 5. This plug has two ends which shall be designated the small end 11 and the large end 12. Protruding from the face of the large end are two contact or connector blades 13 and 14. The usage 25 of this type of contact plug is familiar to everyone.

Returning to the drawing, body 10 is a "one-piece" resilient member so recessed as to be capable of holding blades 13 and 14 most securely and yet it is readily and successfully moldable. If Figures 3 and 5 are inspected it will be seen that with the use of a multiple part mold (see Fig. 5-A), the removal thereof can be had without hindrance. Of the various recesses in body 10, 35 15 and 16 respectively. These slots naturally are tight-fitting around the lower ends of the blades which they hold. At the lower ends of the blade slots 15 and 16 are to be found the blocks which 40 constrict or obstruct the otherwise free passage, except for reasonable friction, of the respective blades through the slots. For blade slot 15 the blocks are numbered 17 and 18 and for slot 16 the blocks are 19 and 20 (see Fig. 4). These 45 blocks are integral with body 10 and are adapted to cooperate with recesses in blades 13 and 14. If blade 13 is taken as an example (Fig. 3) it will be seen that recesses 21 and 22 exactly fit over blocks 17 and 18 respectively whereby blade 13 50 when in final position is keyed or locked in place and prevented from either being pushed further down into or from being pulled out of slot 15. Similarly for blade 14. It is at once apparent that free sidewise movement of the blades is 55 impossible because of the sides of the slots and any edwise movement is prevented by the recesses and blocks just described.

If blade 13 is examined as typical, it will be seen to consist of a flat metallic strip recessed at 60 21 and 22 as above described and with a further recess at 23. Recess 23 is a strain slot designed to help keep any pulling pressure on its wire conductor 24 away from the soldered electrical joint 25 between the wire end 24 and blade 13 65 this by means of a U-turn through recess 23 (see Fig. 3). Indeed, so snug is the fit between blade slot 15 and blade 13 that the end of wire conductor 24 if turned over the top of the central integral wall 26 and down into slot 15 (see Fig. 1) 70 will be firmly held when blade 13 is pushed down therein even if no soldered joint 25 is made.

In assembling the contact plug as shown in Figure 1, the blades have been inserted into body 10 from the large end. This is made possible 75

because the lower ends of the blades do not exceed the upper ends in width, which is uniform where the blades are not recessed. In such an assembly the wire conductors 24 and 27 pass 5 through a circular opening in the center of the plug, are attached to their respective blades 13 and 14 and then with the blades are pressed or pushed down into the respective blade slots. In 10 such assembling, for example, the lower curved end of blade 13 would part the blocks 17 and 18, which yield because of the resilience of body 10 until such blocks come opposite to the recesses 21 and 22 when the spring in the resilient body 10 returns the blocks to their original positions, 15 locking blade 13 in place without any distortion or severe strain being thereby imposed upon the resilient material of body 10. On the face of large end 12, a depression 28 is to be found which permits the wire conductors 24 and 27 to bend 20 over the discontinuous wall 26 without sticking up above the face of the plug.

If Figure 5 is next observed it will be seen that the blade slots 15 and 16 extend downwardly beyond the bottom of wall 26 and into a common 25 channel 29. In the plug of this design the blades with the wire conductors attached may be pressed instead into their final assembled position (see Figure 1) through the small end 11 of the plug. In such a case the blades will be pressed upwardly 30 through the constricting or obstructing blocks, the bevel 30 on the upper ends of the blades assisting in such passage. In such a case, likewise, the wire conductors would not pass through the circular opening 31 in the center and yet the 35 wire conductor cable 32 would be far enough inside of small end 11 to comply with electrical safety regulations.

In molding the plug body shown in Fig. 5, a plural-part mold as shown in Fig. 5A can be used. 40 This mold has the advantage among others of being able to mold the blocks 17, 18, 19 and 20 in the respective blade slots of body 10 and of being removable thereafter without distortion or breakage of any part of the freshly molded body. The 45 mold in question comprises a jacket portion 10a conforming interiorly to the outline of body 10 and two plunger sections. Referring to the drawing, it will be seen that in the plunger sections there is a portion 29a forming the common 50 channel 29, a table portion 28a for the depression 28, spindle portions 66 and 67 needed to form opening 31 and members 65 and 68 to form the blade slots. Reduced portions 18a and 20a of members 65 are responsible for forming the 55 blocks. In molding, a proper sized ball of soft rubber is placed in jacket portion 10a and the plunger sections are then thrust into the jacket portion, sealing it and interacting to form the plug body 10. When the plunger sections are 60 withdrawn, there is no "catching" of any part of the mold or plungers on any part of the plug body and consequently there is no distortion, tearing or breaking of the latter. The principal factor in achieving this result is due to the 65 division of the mold portions forming the blade slots across the reduced portions responsible for forming the blocks. With a few changes which are now readily apparent a successful mold embodying the same principles can also be made for 70 the embodiment of this invention shown in Figures 6 to 9.

The embodiment of the invention shown in Figures 6 through 9, is a preferred form. In this contact plug, body 40 has a small end 41 and a 75 large end 42. The face of end 42 is pierced

solely by the blade slots 43 and 44. There is usually more material at this end than at the small end 41 because any tendency to separation or pinching the blades together is resisted primarily and largely by force by the large end. At 5 the lower end of slot 43 are to be found integral blocks 45 and 46 (for slot 44 but one block 47—Figure 7—is shown). These blocks have the same functions, purposes and action as those described in connection with the embodiment 10 shown in Figure 1. At about the point where the blocks are located, the blade slots open into the upper forked sections of a common channel 48. The forked sections are caused by an integral partition or wall 49 which when the plug 15 is being assembled serves to guide the end of each blade into its respective slot. Ample room is provided in the channel 48 and the forked sections thereof to accommodate the wire conductor ends 50 and cable 50a (see Figure 9). It is 20 also entirely possible to design this plug so as to decrease the length of channel 48 and its sections by lowering wall 49 or some similar change. This would more completely place the blocks 25 actually in the blade slots and would decrease the room in the channel and sections for the wire conductors.

In Figure 9 is blade 51 in assembled position with its recesses 52 and 53 engaging blocks 45 and 46 respectively. The strain recess 54 with 30 the bent over wire end 50 is also shown. As explained previously the snug fit of slot 43 around blade 51 produces maximum surface contact and the steadiness required without having to make a two-piece contact plug. In fact, this preferred 35 form of contact plug provides the most complete, distortionless and satisfactory hold for its blades. Added to this, the entire body 40 is made in one 40 piece. Like the other form shown in this application it can readily be molded with the blocks therein as shown.

In assembling the preferred embodiment, blades arranged substantially as in Figure 7, are pushed into their respective blade slots 43 and 44 until the blade recesses and blocks engage 45 (Fig. 9). All of such assembling is done through small end 41 and the passage of each blade past its obstructing blocks is as previously described for the other embodiment of this invention shown in this application. When assembled, all 50 electrical parts which should be covered are completely protected and insulated and the blades are firmly and immovably held in place without the aid of anything except the contact plug itself.

This invention is not to be limited in any way 55 except as may be done by the appended claims.

I claim:

1. In a contact plug, a one-piece base of resilient flexible material having a central recess adapted to receive a cord and two flat slots extending downwardly therefrom through the plug, said base having integral spaced separate parallel portions in each slot projecting towards each other to form restricted slot passageway portions extending from within each slot into the central recess, said projecting portions having shoulders at each end thereof.

2. In a contact plug, a one-piece base of resilient flexible material having a central recess adapted to receive a cord and two flat slots extending downwardly therefrom through the plug, said base having integral spaced separate parallel portions in each slot projecting towards each other to form restricted slot passageway portions extending from within each slot into the central 70 75 recess.

recess, said projecting portions having shoulders at each end thereof, and straight contact blades seated in said slots, said blades having recessed portions adjacent the upper ends thereof engaging the parallel portions of said slots.

3. In a contact plug, a one-piece base of resilient flexible material having a central recess adapted to receive a cord and two flat slots extending downwardly therefrom through the plug, 10 said base having integral spaced separate parallel portions in each slot projecting towards each

other to form restricted slot passageway portions extending from within each slot into the central recess, said projecting portions having shoulders at each end thereof, and straight contact blades seated in said slots, said blades having recessed portions adjacent the upper ends thereof engaging the parallel portions of said slots, the intermediate portions of said blades below said recessed portions having transverse slots for connecting the cord lead wires.

ARTHUR BROWNSTEIN.
